HOSE SUPPORTER

Gilbert L. Baker and Algot B. Oberg, Oakland,
Calif.

Application March 12, 1932. Serial No. 598,500

3 Claims. (Cl. 24—260)

This invention relates to hose supporters, and has for its object the production of a simple and efficient lady's hose supporter which is so constructed as to efficiently grip the top of a stocking in order to eliminate all danger of creating runs in the hose or stocking.

Another object of this invention is the production of a simple and efficient hose supporter which is provided with two smooth surfaces between which the hose may be firmly clamped, thereby eliminating the necessity of drawing down the clamping member over the hose which would be likely to cause a run.

A further object of this invention is the production of a simple and efficient hose supporter and clasp which will efficiently grip the top of the hose and firmly support the same in engagement with the supporting elastic.

With these and other objects in view, this invention consists of certain novel constructions, combinations and arrangements of parts as will be hereinafter fully described and claimed.

In the drawing:—

Figure 1 is a front elevation of the hose supporter and clasp;

Figure 2 is a rear elevation of the structure shown in Figure 1;

Figure 3 is an edge elevation of the structure shown in Figures 1 and 2;

Figure 4 is a section taken on line 4—4 of Figure 1;

Figure 5 is a section taken on line 5—5 of Figure 1;

Figure 6 is a section taken on line 6—6 of Figure 1;

Figure 7 is a detail perspective view of the hose supporting clip, the swinging jaw being shown in an open position, the clip also being shown in engagement with a wide strip of supporting elastic; and

Figure 8 is a vertical sectional view through the supporting elastic illustrated in Figure 7 showing the sliding buckle mounted in an adjusted position upon the supporting elastic.

By referring to the drawing, it will be seen that 1 designates the body of the hose supporting clip which is preferably formed of a metallic structure comprising a pair of interfitting sections 2 and 3, each of the interfitting sections 2 and 3 having 50 side flanges 4 and 5 which are adapted to abut and suitable rivets or other securing means 6 may be employed for securing these flanges 4 and 5 together, thereby holding the interfitting sections 2 and 3 in an assembled relation. The section 2 of the clip 1 is provided with a stationary

jaw 7 having a transversely extending inwardly rolled lip 8 along the lower extremity. A hinged jaw 9 is hingedly secured to the section 3 by means of a supporting pintle 10 which extends through the flanges 4 of the section 2 of the clip, 60 the jaw 9 having a rolled portion 11 which fits snugly around the supporting pintle 10. This hinged jaw 9 carries a filler strip 12 between the inwardly bent lips 13 of the side flanges 14 of the hinged jaw 9 and this filler strip or cleat 12 65 is secured to the jaw by the inwardly turned clamping portions 13 and also the studs 15 which extends through suitable apertures formed in the hinged jaw 9, as illustrated. This cleat 12 is preferably convex in cross section and is adapted 70 to be brought into interlocking relation with the inwardly turned rib 8 of the stationary jaw 7 and firmly grip the stocking 16 therebetween and efficiently hold the stocking in engagement with the clasp or clip.

A sliding clip 17 is slidably mounted upon the clasp 1 and is movable longitudinally thereof and this sliding clip 17 is provided with end flanges 18 which are in turn bent rearwardly of the clasp 1 to provide retaining hooks 19, as shown in 80 Figure 6 and thereby permit a sliding clip to be freely movable longitudinally of the clasp 1. A finger-grip portion preferably struck outwardly from the sliding clip is provided, as indicated at 20, to facilitate the movement of the clasp 1. By 85 carefully considering the drawing, it will be seen that the stationary jaw 7 by having the transversely extending inwardly bent rolled rib 8 in conjunction with the rounded cleat 12 will produce an efficient friction grip for the stocking 90 which will be of material length extending transversely across the top of the stocking so as to prevent the breaking of the fibre of the stocking and also prevent the starting of a run, due to this wide gripping feature of the jaw which will firmly 95 clamp the stocking throughout the transverse area of the clasp. The sliding clip 17 is of such a structure as to cause the hinged jaw 9 to be readily swung into firm clamping engagement with the stationary jaw 7 as the sliding clip 17 is moved 100 downwardly toward the lower end of the clasp 1.

The clasp 1 is provided with suitable threading apertures 22, 23, 24, and 25, through which narrow supporting elastic 26 may be threaded, suitable teeth 27 being employed in the aperture 25 and suitable teeth 28 being employed in the aperture 23 to efficiently grip the elastic as is obvious from the drawing, and hold the elastic in a firm position to prevent slipping. The elastic 26 may be supported in any suitable or desired manner 110

to a girdle, it being usual to use the narrow elastic for this purpose.

When it is desired to use the clip in conjunction with corsets, the wider band of elastic illustrated and indicated by the numeral 29 may be employed upon which wider strip of elastic 29 may be adjusted the sliding buckle 30 having two rows of adverse teeth indicated by the numerals 31 and 32 in Figures 7 and 8. Through the medium of this sliding buckle 30 a proper adjustment of the elastic 29 may be had. A suitable link 33 may be clipped into engagement with the clasp 1 as shown in Figure 7, for attaching the wide band of elastic 29 to the clasp 4. By means of the structure just described, it will be seen that the clasp may be readily attached to the elastic without the necessity of sewing or stitching the elastic to the clasp, due to the arrangement of the sliding buckle 30 when wide elastic is used, and also due to the manner of threading the elastic 26 through the respective apertures formed in the clasp, as shown in Figure 4.

It should be understood of course that certain detail changes in the mechanical structure so far as this connection is concerned may be employed without departing from the spirit of the invention so long as these changes fall within the scope of the appended claims. It should also be understood that a very simple and efficient structure has been produced which would not require skill to replace the elastic in the metal part in order to attach the clasp to a piece of elastic. Further, it will be noted that a very safe support has been provided for ladies' hose which will also eliminate the danger of creating runs in the hose, in view of the fact that the stationary and hinged jaws will have an even contact on the material, and these jaws will be firmly secured together by means of the sliding clasp, to provide an even tension over the entire width of the jaws.

Having described the invention, what is claimed as new is:—

1. A hose supporter of the class described comprising a body having a pair of interlocking sections, each section having inturned flanges, the

flanges of one section overhanging the flanges of the adjoining section, means for locking said flanges together, a stationary jaw carried by one section, a hinged jaw carried by the other section, stocking gripping means carried by said jaws, and means for clamping said jaws together to provide stocking-gripping portions along the contacting points of said jaws. 80

2. A clasp for use in connection with hose supporters comprising a body having a stationary jaw, a hinged jaw, a pintle carried by said stationary jaw, said hinged jaw being provided with a rolled portion fitting over said pintle for constituting a hinge for said hinged jaw, each jaw being provided with a substantially wide smooth gripping portion at the extremity thereof, a sliding clip mounted upon said stationary jaw and adapted to be brought down over said hinged jaw for firmly clamping said hinged jaw to said stationary jaw, said sliding clip being provided with rearwardly bent overhanging ends for retaining said clip upon said clasp, and a finger-hold formed upon the front of said sliding clip. 90

3. A clasp of the class described comprising a body formed of a pair of interfitting sections, one of said sections having a projecting end constituting a stationary jaw, the terminal of said stationary jaw being slightly inturned and having a transversely extending relatively long smooth gripping portion, the other section having a hinged jaw secured near one end thereof, said hinged jaw having an elongated substantially wide and smooth gripping extremity adapted to register with the extremity of said stationary jaw for producing a clamping action, and a sliding clip slidably mounted upon the said stationary jaw and adapted to be moved over said hinged jaw for firmly clamping said hinged jaw upon said stationary jaw, said clip being capable of movement entirely away from said hinged jaw whereby said hinged jaw may be swung to a wide open position relative to said stationary jaw. 110
